(57) **CLAIM**

The ornamental design of a “button”, as shown and described.

DESCRIPTION

FIG. 1 is a front view illustrating the male portion of the “button”

FIG. 2 is a rear elevation thereof

FIG. 3 is a right side view thereof

FIG. 4 is a left side view thereof

FIG. 5 is a plan view thereof

FIG. 6 is a bottom plan view thereof

FIG. 7 is a section view thereof taken along with the line 7—7 of FIG. 1

FIG. 8 is a section view thereof taken along with the line 8—8 of FIG. 2

FIG. 9 is a front view illustrating the female portion of the “button”

FIG. 10 is a rear elevation thereof

FIG. 11 is a right side view thereof

FIG. 12 is a left side view thereof

FIG. 13 is a plan view thereof

FIG. 14 is a bottom plan view thereof

FIG. 15 is a section view thereof taken along with the line A—A' of the front view in FIG. 9

FIG. 16 is a section view thereof taken along with the line B—B' of the rear elevation in FIG. 10

FIG. 17 is a front view illustrating the female portion and male portion of the button, being detachably connected.

FIG. 18 is a rear elevation thereof

FIG. 19 is a right side view thereof

FIG. 20 is a left side view thereof

FIG. 21 is a plan view thereof

FIG. 22 is a bottom plan view thereof

FIG. 23 is a section view thereof taken along with the line 23—23 of FIG. 17

FIG. 24 is a section view thereof taken along with the line 24—24 of FIG. 18

FIG. 25 is an enlarged perspective view of the male portion having a central protrusion

FIG. 26 is an enlarged perspective view of the female portion having a central recess

FIG. 27 is an enlarged perspective view of the male portion and female portion, being opposite each other; and,

FIG. 28 is an enlarged perspective view of the male portion and female portion, being detachably connected.

The “button” comprises a combination of two portions, i.e., a male portion and a female portion. The female portion is provided with a cylindrical magnet. The male portion is detachably connected with the female portion by magnetic attraction of a cylindrical magnet.
